UNITED STATES PATENT OFFICE

100,551

DESIGN FOR A PIPE CLEANING ASHTRAY

Edward T. Diviny, Baltimore, Md.

Application May 2, 1936, Serial No. 62,424

Term of patent 14 years

To all whom it may concern:

Be it known that I, Edward T. Diviny, a citizen of the United States, residing at the city of Baltimore, State of Maryland, have invented a new, original, and ornamental Design for Pipe Cleaning Ashtrays, of which the following is a specification, reference being had to the accompanying drawing, forming part thereof.

Figure 1 is a plan view, and

Figure 2 is a side elevational view, partly in section of a pipe cleaning ashtray embodying my new design.

I claim:

The ornamental design for a pipe cleaning ashtray substantially as shown.

In testimony whereof I affix my signature.

EDWARD T. DIVINY.
